UNITED STATES PATENT OFFICE

HYMAN GUSSAK, OF NEW YORK, N. Y.

COMBINATION SHIRT AND DRAWERS

Application filed July 9, 1930. Serial No. 466,800.

The present invention relates to improvements in men's garments and has reference more particularly to a combination shirt and drawers.

5 The principal object of the present invention is to provide a garment of the above mentioned character which will combine, in a unitary structure, an outer shirt as distinguished from an undershirt, and a pair of drawers.

10 Another important object is to provide a combination shirt and drawers that will afford maximum comfort to the wearer, the garment being of such construction as to permit the same to be readily and easily put on or taken off.

15 A further object is to provide a combination shirt and drawers which is simple in construction, inexpensive, strong and durable and further well adapted to the purposes for which it is designed.

20 Other objects and advantages of the invention will become apparent from the following description when taken in connection with the accompanying drawings.

In the accompanying drawings wherein like reference characters indicate corresponding parts throughout the several views:

25 Figure 1 is a front elevation of the combination shirt and drawers embodying my invention.

Figure 2 is a side elevation thereof.

30 Figure 3 is an enlarged fragmentary perspective view of the drawers forming a salient part of the present invention, and

Figure 4 is a vertical sectional view taken approximately on the line 4-4 of Figure 1.

35 In the drawings, wherein for the purpose of illustration is shown the preferred embodiment of my invention, the numeral 1 designates generally the outer shirt, the same including the front 2 and the back 3, the back being connected to the front by the usual side seams. The sleeves of the shirt are indicated at 4 and the neckband at 5.

40 The front 2 is open and the vertical opening is closed by the customary buttons denoted by the numeral 6. It is to be understood that the front opening commences at

the neckband and extends downwardly to the crotch portion 7.

45 The drawers portion of the garment is denoted generally by the numeral 8 and the fronts of the two legs of the drawers are indicated at 9, said frontal portions forming a continuation of the respective portions of the front 2 of the shirt. Cooperating with the frontal portions 9 are the rear leg portions 10, the rear leg portions forming a continuation of the back 3 of the shirt.

50 Laterally extending tabs 11 and 12 are associated with the interposed edge portions of the fronts 9 at the crotch portion 7, said tabs being adapted for disposition in overlapping relation when in use. A button 13 is attached to one tab while a button-hole 14 is formed in the complementary tab for receiving the button 13 to secure the tabs in overlapping engagement for a purpose to be presently described.

55 The lower edge of the back portion of the drawers is cut to form a substantially V and attached to the V-shaped edge portion is a strip of fabric of the same material as the shirt and drawers. This strip of material includes a central V-shaped tongue 14' and corner wings 15.

60 In Figure 3 of the drawings, there is clearly illustrated the manner in which the portions of the material constituting the drawers are arranged when the garment is worn and it will be observed that the tongue 14' is brought underneath of the crotch portion of the garment and is adapted to be attached 65 to the lowermost button of the row of buttons that connect the divided front portions of the shirt together, it being of course understood that the tongue 14' is provided with a button hole such as is indicated at 16.

70 The free edge portions of the front sides of the legs of the drawers will be disposed in overlapping relation with respect to the corner wings 15 that form continuations of the inner side edges of the back portions of the legs and if desired, any suitable fastening means may be associated with the overlapping portions of the legs of the drawers.

75 The cooperating laterally disposed tabs are disposed across the tongue 14' and are con-

nected together as indicated at Figures 1 and 4 so as to form the complete unitary garment.

A combination outer shirt and drawers of the above mentioned character can be readily and easily put on or taken off and will at the same time, not interfere with the ordinary movements of the body of the wearer. Furthermore, the construction of the drawers is such as to permit the same to be easily operated for purposes of utility.

Although I show a shirt open at the front with collar attached and sleeves it is to be understood that I do not wish to limit myself to the construction as the invention is equally well applicable to a shirt with or without an opening in the front, with or without attached collar and with or without sleeves.

20 A garment of this character will be strong and durable yet inexpensive in its manufacture.

While I have shown the preferred embodiment of the invention, it is to be understood that minor changes in the size, shape and arrangement of parts may be resorted to without departing from the spirit of the invention and the scope of the appended claims.

Having thus described the invention what

30 I claim is:

1. A combination shirt and drawers comprising a shirt including a back, and a front, the drawers including front portions forming continuations of the lower portions of the front of the shirt, a back portion forming a continuation of the back of the shirt, and a portion extending forwardly from the back to form inner side portions for legs of the drawers and a crotch portion, the said crotch 40 portion having its front end extending upwardly and releasably secured to the front of the shirt, and tongues overlapping the front end of the crotch portion transversely thereof and secured to each other.

45 2. A combination shirt and drawers comprising a shirt including a back, and a divided front, the drawers including front portions forming continuations of the lower portions of the respective sections of the divided front of the shirt, a back portion forming a continuation of the back of the shirt, and a tongue extending from the central portion of the back of the drawers at the lower edge thereof for disposition at the crotch of the 50 garment and being detachably connected to the lower portion of the shirt at the meeting edges of the divided front, and laterally extending tabs carried by the inner opposed free edge portions of the front sections of the drawers for disposition in overlapping relation across the tongue, and means for connecting the tabs detachably together.

55 3. A combination shirt and drawers comprising a shirt including a back, and a front, the drawers including front and rear por-

tions forming continuations of the lower portions of the front and rear portions of the shirt, a continuation of the back of the shirt being extended forwardly to form inner sides of the legs of the drawers and a crotch terminating in a tongue adapted to be detachably connected to the front of the shirt, the front portions of the legs of the drawers overlapping the inner side portions thereof and having transversely extending tabs disposed in overlapped relation to the tongue at the front of the crotch and releasably united in overlapped relation to each other.

4. A combination shirt and drawers comprising a shirt including a back, and a divided front, the drawers including front portions forming continuations of the lower portions of the respective sections of the divided front of the shirt, a back portion forming a continuation of the back of the shirt, and a tongue extending from the central portion of the back of the drawers at the lower edge thereof for disposition at the crotch of the garment and being detachably connected to the lower portion of the shirt at the meeting edges of the divided front, the free edge portions of the fronts of the drawers being disposed in overlapping relation with respect to the adjacent portions of the back portions of the drawers, and laterally extending tabs carried by the inner opposed free edge portions of the front sections of the drawers for disposition in overlapping relation across the tongue and means for connecting the tabs detachably together.

5. In a garment of the class described, a shirt including a back, a divided front, means for fastening the adjacent edges of the front sections together, drawers including front portions forming continuations of the respective portions of the divided front of the shirt, and a back forming a continuation of the back of the shirt, a tongue extending from the central lower edge portion of the back of the drawers for disposition beneath the crotch of the garment and adapted to be detachably connected to the fastening means at the lower edge portion of the divided front of the shirt, corner wings forming continuations of the inner side edge portions of the rear leg portions of the drawers, the front leg portions of the drawers being disposed in overlapping relation with respect to said wings and at their upper ends carrying tabs extending transversely therefrom and secured to each other in overlapping relation to the tongue.

6. In a garment of the class described, a shirt including a back, a front, drawers including front portions formed of the lower portions of front of the shirt, and a back formed of the lower portions of the back of the shirt, a portion of the back of the drawers being extending forwardly to form a crotch and inner side portions of the legs of the

drawers, the crotch forming portion terminating at its front in a tongue extending upwardly and adapted to be releasably secured to the front of the shirt, the front leg portions of the drawers being disposed in overlapping relation with respect to the inner side portions of the legs, and tabs extending laterally from the inner side edges of the front leg portions of the drawers at the crotch portion of the garment for disposition in overlapping relation across the tongue, and means for securing said tabs in their overlapped position.

In testimony whereof I affix my signature.
HYMAN GUSSAK.
